(57) **CLAIM**

We claim the ornamental design for a garden irrigation micro dripper, as shown and described.

DESCRIPTION

FIG. 1 is a top elevational view of a garden irrigation micro dripper comprising the new design.

FIG. 2 is a bottom elevational view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a perspective view thereof; and,

FIG. 8 is a perspective view thereof showing a spike in phantom broken lines for purposes of illustrating environmental structure only.

The broken lines shown in the drawings illustrate portions of the garden irrigation micro dripper that form no part of the claimed design.
